UNITED STATES PATENT OFFICE

161,211

HASSOCK

Anthony Saccoccia, Providence, R. I.

Application February 23, 1950, Serial No. 8,055

Term of patent 14 years

(Cl. D15—8)

To all whom it may concern:

Be it known that I, Anthony Saccoccia, a citizen of the United States of America, residing at Providence, county of Providence, State of Rhode Island, have invented a new, original, and ornamental Design for a Hassock, of which the following is a specification, reference being had to the accompanying drawing, forming a part thereof:

Fig. 1 is a perspective view looking at one side of a hassock showing my new design; and

Fig. 2 is a perspective view looking at the other side thereof.

I claim:

The ornamental design for a hassock, substantially as shown.

ANTHONY SACCOCIA.
